Cochran Freund & Young LLC(57) **CLAIM**

The ornamental design for a liquid container bottle, as shown and described.

DESCRIPTION

FIG. 1 is a rear isometric view of a liquid container bottle showing our new design.

FIG. 2 is a top isometric view thereof;

FIG. 3 is a rear elevation view thereof;

FIG. 4 is a front elevation view thereof;

FIG. 5 is a right side elevation view thereof of which the left side elevation view is a mirror image;

FIG. 6 is a top plan view thereof; and,

FIG. 7 is a bottom plan view thereof.

The broken lines in the drawings depict portions of the liquid container bottle that form no part of the claimed design.
